UNITED STATES PATENT OFFICE.

WILLIAM LEIGHTON, JR., OF WHEELING, WEST VIRGINIA.

DESIGN FOR THE ORNAMENTATION OF DISHES OR VESSELS.

SPECIFICATION forming part of Design No. 16,994, dated November 23, 1886.

Application filed August 4, 1886. Serial No. 210,023. Term of patent 3½ years.

To all whom it may concern:

Be it known that I, WILLIAM LEIGHTON, Jr., residing at Wheeling, in the county of Ohio and State of West Virginia, a citizen of the United States, have invented or discovered 5 a certain new and original Design for the Ornamentation of Dishes or Vessels, of which the following is a specification.

In the accompanying drawings, which make 10 part of this specification, Figure 1 is a view in side elevation of a glass dish, showing a portion of my new design. Fig. 2 is a similar view showing another portion of the design.

My new design for the ornamentation of the 15 surface of dishes or vessels consists of a shield or heart shaped figure, 1, which may be filled in with a scroll ornamentation resembling bunches of ribbons, as at 2. One, two, or more of these shields are arranged around the dish 20 or vessel to be ornamented, the spaces on each side of them being filled with rows of Maltese crosses 3, separated by a series of two or more angular ribs, 4. Around the top edge of the 25 dish or vessel, and on opposite sides of the shield-like figures, are arranged a series of fans, 5.

I claim herein as my invention—

1. In a design for a dish or vessel, one or more shield or heart shaped figures, a series of Maltese crosses, and a series of fan-like figures on opposite sides of the shields, as described and shown.

2. In a design for a dish or vessel, one or more shield or heart shaped figures filled with scroll ornamentations, a series of Maltese 35 crosses, and a series of fan-like figures on opposite sides of the figures, as described and shown.

3. In a design for a dish or vessel, one or more shield or heart shaped figures, a series 40 of Maltese crosses, a series of angular ribs between the crosses, and a series of fan-like figures, as shown and described.

In testimony whereof I have hereunto set my hand.

WILLIAM LEIGHTON, JR.
